Primary Examiner—Alan P. Douglas

Assistant Examiner—Antoine D. Davis*Attorney, Agent, or Firm*—Merchant, Gould, Smith, Edell, Welter & Schmidt[57] **CLAIM**

The ornamental design for display enclosure with display, as shown and described.

DESCRIPTION

FIG. 1 is a perspective view showing a preferred embodiment of my new design in one environment of use; FIG. 2 is a side elevational view showing my new design in one environment of use the opposite side being a mirror image;

FIG. 3 is a top elevational view thereof;

FIG. 4 is a front elevational view thereof;

FIG. 5 is a bottom elevational view thereof;

FIG. 6 is a rear elevational view thereof;

FIG. 7 is a perspective view of an alternative embodiment of my new design shown in one environment of use;

FIG. 8 is a side elevational view of the alternative embodiment of my new design shown in one environment of use the opposite side being a mirror image;

FIG. 9 is a top elevational view of the alternative embodiment of my new design;

FIG. 10 is a front elevational view of the alternative embodiment of my new design;

FIG. 11 is a bottom elevational view of the alternative embodiment of my new design; and,

FIG. 12 is a rear elevational view of the alternative embodiment of my new design.

The broken line showing of a scale platform, mounting bracket and fasteners are for illustrative purposes only and forms no part of the claimed design.

The display screen shown in FIGS. 4 and 10 has been omitted for ease of illustration in FIGS. 1 and 7.
